Charles E. Morgan, INVENTOR,

Charles Turner Brown, BY
ATTORNEY.

UNITED STATES PATENT OFFICE.

CHARLES E. MORGAN, OF CHICAGO, ILLINOIS.

AIR-HEATER FOR FURNACES.

1,311,611.

Specification of Letters Patent. Patented July 29, 1919.

Application filed January 27, 1919. Serial No. 273,240.

To all whom it may concern:

Be it known that I, CHARLES E. MORGAN, a citizen of the United States, and a resident of Chicago, in the county of Cook and State 5 of Illinois, have invented certain new and useful Improvements in Air-Heaters for Furnaces, of which the following, when taken in connection with the drawings accompanying and forming a part hereof, is 10 a specification.

This invention relates to the fire box of water heating and steam generating boilers.

Among the objects of the invention are to obtain means for supplying heated air to the 15 fire box of a boiler above the burning body of fuel therein, and to so direct the flow thereof as to accelerate combustion and obviate the production of any considerable quantity of smoke; and to obtain an apparatus 20 which is simple in construction, easily understood and installed, economical, durable, not liable to get out of order, to become broken or otherwise injured either by handling or by the heat or other conditions 25 existing in said fire box, and applicable to old as well as new installations.

In said drawings illustrating a device which embodies this invention Figure 1 is a 30 side elevation of a boiler, with a portion of the side wall broken away to expose to view the interior thereof and a device embodying this invention installed therein.

Fig. 2 is a vertical section transversely of the fire box, showing the device embodying this invention in side elevation.

Fig. 3 a vertical section, on line 3—3 of Fig. 2, viewed in the direction indicated by the arrows.

Fig. 4 is a perspective of the inside member of the device, and

Fig. 5 is a perspective of the outside member of said device.

Fig. 6 is an elevation of a modification of the construction which is illustrated in Figs. 40 1 to 5, inclusive; and

Fig. 7 is a vertical section on line 7—7 of Fig. 6, viewed in the direction indicated by the arrows.

A reference character applied to designate 50 a given part indicates said part throughout the several figures of the drawings wherever the same appears.

A represents a hot water boiler; B, B, B, the water chambers or spaces of the boiler; 55 C the fire box. D represents fuel; and E grate bars. F represents the outgoing flue

of the fire box. G represents the outer shell of a device embodying this invention. Shell G is shown in Fig. 1 installed in fire box C, adjacent to discharge flue F and above the fuel on grate bars E. H, H, represent air inlet apertures in the ends of shell, G. I, (Fig. 4) represents the base of shell, and J discharge outlets or passage ways. j, j, represent inclined faces 60 forming the bottoms of the outlets J, and extending forward from the back of the chamber in shell G, and downward, to determine the direction of flow of air discharged from the device into the fire box. The arrows X indicate the direction of the flow of air from the device and in the fire box C. K, K, (Figs. 3 and 4), represent baffle plates. L, L, also represent baffle plates which are illustrated as being maintained in place by 65 resting against the ends k, k, of baffle plates K, K, with bars M of base I extending along the lower edges of said plates L.

In the modification which is illustrated in Figs. 6 and 7, the shell (G'), is made in two 70 parts, respectively provided with flanges g, g, and joined by the bolts g', g'. The baffle plate K' extends longitudinally in the chamber of the device from the front to the rear walls thereof; and baffle plates L' are curved. 75

The several baffle plates K, L, and K', L', are heated by conduction from the base I and shell G of the device; and air flowing through said shell is warmed by convection from said baffle plates as well as from the 80 shell and base. Said baffle plates also direct the course of said air flowing through the device.

N, N, represent bolts to attach base I to shell G.

The operation of the device, when installed in place in a fire box, is as follows:— The draft of the fire box induces a flow of air from the device, through outlet passage ways J, J, and said flow is supplied from an inflow through apertures H, H. Air flowing into the device through said apertures H, H, is directed upward by the baffle plates L, L, (or L', L'), and after passing over said baffle plates flows downward, over plates K, 95

K, (or K'), to and through the outlet passage ways J, J, into the fire box C. The flow of the air through the device, as above described, heats and expands it, and it is discharged into the fire box above the fuel 100 on the grate bars, and into the gases from said fuel. The direction of the discharge 105

intermixes said air and gases, and said air being at a high temperature good combustion takes place.

I claim:

- 5 1. An air supply and heating device consisting of side and end walls, a top and a separable base arranged to form a shell provided with a chamber, said chamber provided with inlets positioned in the end walls of the shell adjacent to said base, and with outlets positioned on the upper face of said base and consisting of grooves the bottoms whereof are inclined downward from the inlet ends thereof, in combination with baffle plates 10 in said chamber, some thereof arranged to direct air flowing thereinto to above the remainder thereof, and said remainder of said baffle plates disposed in said chamber to direct air in the upper portion 15 of the chamber downward to said outlets and underneath the one of said side walls which is positioned over said outlets, said outlets arranged so that air flows therefrom, and from said chamber, at substantially right angles to the flow thereof in said chamber.
- 20 25

2. An air supply and heating device consisting of walls, a top and a separable base arranged to form a shell provided with a chamber, said chamber provided with inlets positioned in the end walls of the shell adjacent to said base and with outlets positioned on the upper face of said base and consisting of grooves the bottoms whereof are inclined downward from the inlet ends thereof, in combination with baffle plates in said chamber and means, consisting of separable ones of said baffle plates resting on said base, to direct air flowing into said chamber, through said inlets, upward and to above said baffle plates, and the remainder of said baffle plates disposed to direct said air downward to said outlets, to flow underneath the side wall which is over said outlets and from said chamber at substantially right angles to the flow thereof in said chamber.

CHARLES E. MORGAN.
